Attorney-

UNITED STATES PATENT OFFICE.

JOHN RICE, JR., OF EASTON, PENNSYLVANIA.

DUMP CAR.

Application filed April 3, 1925. Serial No. 20,419.

The present invention relates to dump bodies for railway cars, motor trucks, and the like, and appertains more especially to that type of dump body wherein a door or side wall at one side is hingedly connected to the bottom or at one edge of the bottom to swing outwardly and downwardly substantially flush with the bottom when the body is tilted toward the corresponding side.

10 It is the object of the invention to provide extremely simple and inexpensive means for supporting the door or side wall when opened by the tilting movement of the body and for closing the door or wall when the body is restored to normal or horizontal position, in order that the door operating means will consist of a minimum number of parts, to reduce the cost of installation and upkeep, as well as providing other advantages.

15

Another object is the provision of such a device comprising a simple connection between the door or side wall of the body, and support on which the body is mounted, for automatically operating the door or side wall when the body is swung to dumping and normal positions.

With the foregoing and other objects in view, which will be apparent as the description proceeds, the invention resides in the construction and arrangement of parts, as are hereinafter described and claimed, it being understood that changes can be made within the scope of what is claimed, without departing from the spirit of the invention.

The invention is illustrated in the accompanying drawings, wherein—

Figure 1 is an end view of a dump body showing the improvements applied, with the body in normal position.

Fig. 2 is an end view showing the body tilted to dumping position.

Fig. 3 is a plan view of the body in normal position, portions being broken away.

Fig. 4 is a detail view illustrating a modification.

Fig. 5 is an end view of a dump body showing another modification, the body being shown in normal position in full lines and in dumping position in dotted lines.

Figs. 6 and 7 are end views corresponding with Fig. 5 and showing other modifications.

Fig. 8 is a diagrammatical view showing the improvements incorporated in a two-way dump body.

Referring particularly to Figs. 1, 2 and 3, the body 14 may be of any suitable size and may be the body of a railway car, wagon, motor truck, or the like. The bottom of the body is hinged, as at 15, on a support, which, as shown, includes longitudinal sills 16 on a base or plate 17 although any other suitable support may be used. One side wall 18 of the body provides a door which is hinged, as at 19, to the corresponding edge of the bottom of the body, so that said door or side wall may swing downwardly and outwardly to a position substantially flush with the bottom for the discharge of the material in the body over the door or side wall 18. The hinge 15 is located nearer the side of the body which has the door 18 than the opposite side, in order that when the body is tilted toward that side where the door 18 is located, the body will swing back to normal or horizontal position under its own weight.

The door operating means consists of a cable or other suitable flexible element 20 at each end of the body having its upper end secured, as at 21, to one end of the door 18 and having its lower end secured, as at 22, to the body support, such as the end of the sill 16 to which the body is hinged. Nails, screws or other securing elements may be used for fastening the ends of each cable or flexible element 20 with the door and body support, in order that the cables may be conveniently and quickly fastened in place. Each cable 20 extends through an aperture in an arm 23 secured to the projecting end portion of the door 18 beyond the end of the body and projecting inwardly or toward the opposite side of the body above the hinge 19. As shown, the arm 23 constitutes part of an angle piece or member 24 secured to the inner side of the projecting end portion of the door 18. The points at which the ends of the cables or flexible elements are secured to the door and body support may be quickly determined, without requiring accurate plotting in building or rebuilding a car, or in making readjustments due to wear and tear. This provides for simplicity and cheapness in cost, both in installation and maintenance.

The arm 23 is of such length, and the point of attachment 22 is so located, that when the body is tilted to dumping position, as seen in Fig. 2, the flexible elements 20 are disposed above the axis of the hinge 19, whereby said flexible elements will support

the door 18, said door swinging outwardly and downwardly by the pressure of the material within the body when the body is tilted, so that the door swings open for the discharge of the material across the door. When the body is swung back to normal position, the tension on the cables or elements 20 will swing the door upwardly and inwardly to closed position, as seen in Fig. 1. The door 18 has a compound movement, inasmuch as it swings with the body, and also swings relatively to the body, and in all positions of the door the flexible elements 20 are under tensile strain for supporting the door or holding it against the body. It is thus possible to use cables, wire ropes or other flexible elements for the connections between the door and body support, inasmuch as said connections are always under tensile strain and are not subjected to compression strains. The flexible elements 20 also bend where they pass through the arms 23, as apparent by reference to Figs. 1 and 2 showing the two extreme positions. However, the distance between the point of attachment 22 and aperture of the arm 23 through which each element 20 passes remains the same so that the element 20 does not slide through the arm 23; thereby avoiding a rubbing or chafing action, so that the element 20 will not wear out quickly.

It will be noted that when the body is moved to dumping position, the hinge 19 moves downwardly closer toward the points of attachment 22, thereby slackening the elements 20 so that the door 18 may swing open, whereas when the body is returned to normal position, the hinge 19 is moved upwardly further away from the points 22 then when the body is in dumping position, so that the elements 20 pull the door to closed position as the body is swung from dumping to normal position. The points 22 of attachment of the elements 20 are therefore located below the hinge 15 between the body and body support, while the connection of the elements 20 with the door 18 must be such that the elements 20 will pull on the door 18 in all positions of the body.

Fig. 4 illustrates a modification wherein the arm 23' has a pair of rollers 25 between which the cable or flexible element 20 passes, thereby reducing friction.

Fig. 5 illustrates the hinge 15 of the body 14' spaced a different distance from the door 18, and an arm or bar 26 is secured to and projects from the base or plate 17 of the body support for the connection, as at 22a, of the flexible element 20a.

Fig. 6 shows the use of bars 20b and 20e in lieu of the flexible element, the opposite ends of said bars being pivotally fastened, as at 21b and 22b, to the door 18 and body support, respectively, in the same manner that the flexible element 20 is fastened as shown in

Figs. 1 and 2. The adjacent ends of the bars 20b and 20e are pivotally connected together and to the arm 23b, as at 25b. These bars 20b and 20e will act the same as the flexible element 20 of Figs. 1 and 2, said bars pivoting at the arm 23b and being under tensile strain the same as the flexible element 20.

Fig. 7 shows the use of a rod or link 20d having its upper end pivotally engaged in an arm 23d secured to the door 18, and having its lower end pivotally engaged through an aperture in a plate 22d secured to the corresponding end of the body support. The aperture of the plate 22d in which the link 20d or rod 20d engages may be readily determined, and it will be noted that in this construction, as well as the others, the tension member or connection between the door and body support is above the axis of the door hinge when the body is in dumping position with the door swung open, and the tension connection or member will pull the door to closed position when the body is returned to normal position.

Fig. 8 illustrates in diagram the use of the improvements on a two-way dump body, 14e indicating the bottom of the body to the opposite edges of which are hinged, as at 19e, the opposite side doors 18e. The bottom 14e is hinged at the longitudinal center line, as at 15e, on the frame 17e of the truck or car, so that the body may be tilted toward either side to dumping position. Each door 18e has the inwardly extending arm 23e to which the link or connection 20e is connected, as at 25e, and the lower ends of the links or elements 20e are connected, as at 22e, with the frame 17e in the manner hereinbefore described. When the body is dumped toward either side the link or element 20e at the opposite side is disconnected from the frame 17e so as to permit the corresponding side door 18e to move upwardly with the body while the side door which is moved downwardly will swing open. For example, Fig. 8 shows, in dotted lines, the body tilted toward the right, with the right side door swung open, and the left side door raised with the body and its link or connection 20e disconnected from the frame 17e and hanging loosely. In the same way, the body may be dumped toward the left, with the left hand link or element 20e connected to the frame 17e and the right hand link 20e disconnected from said frame.

Having thus described the invention, what is claimed as new is:—

1. The combination with a support and a dump body mounted thereon for tilting movement to normal and dumping positions and having a door at one side hinged at one edge of the bottom of the body to swing open downwardly when the body is moved to dumping position, of a tension connection be-

tween said support and door so connected to the support and door, free from the body excepting the door, that said connection will support the door when the body is moved to dumping position and door opened and will pull the door closed when the body is moved to normal position.

2. The combination with a support and a dump body mounted thereon for tilting movement to normal and dumping positions and having a door at one side hinged to swing open outwardly and downwardly substantially flush with the bottom of the body when the body is tilted to dumping position, of a direct tension connection between said support and the door of the body, free from the body excepting said door, and arranged to support the door, when opened, directly from the support, and to pull the door closed when the body is returned to normal position.

3. The combination with a support and a dump body mounted thereon for tilting movement to normal and dumping positions and having a door at one side hinged to swing open outwardly and downwardly substantially flush with the bottom of the body when the body is tilted to dumping position, and a tension connection between said support and the door only of said body so connected to the support and door that said connection remains above the axis of the door hinge when the body is tilted to dumping position so as to support the door in open position, and to pull the door to closed position when the body is returned to normal position.

4. The combination with a support and a dump body mounted thereon for tilting movement to normal and dumping positions and having a door at one side hinged to swing open outwardly and downwardly substantially flush with the bottom of the body when the body is tilted to dumping position, of an arm secured to the door and projecting inwardly therefrom above the door hinge, and a connection between the support and the door only of said body engaging said arm for supporting, under tension, the door when opened by the movement of the body to dumping position, and for pulling the door to closed position when the body is returned to normal position.

5. The combination with a support and a dump body hingedly mounted thereon for tilting movement to normal and dumping positions and having a door at one side hinged to swing open outwardly and downwardly substantially flush with the bottom of the body when the body is tilted to dumping position, and a tension connection between said support and the door only of said body, said connection being attached to the support at a point lower down than the hinge of the body and support so that

the door hinge moves closer to and away from said point when the body is moved to dumping and normal positions, respectively, in order that said connection slackens to permit the door to swing open when the body is tilted to dumping position and pulls the door to closed position when the body is returned to normal position, and the attachment of said connection with the door being arranged to space the tension connection above the axis of the door hinge when the body is tilted to dumping position.

6. The combination of a support and a dump body mounted thereon for tilting movement to normal and dumping positions and having a door at one side hinged at one edge of the bottom of the body to swing open downwardly when the body is tilted to dumping position, of a flexible element free from said body excepting the door connected at opposite extremities to the door and support at such points as to pull the door closed when the body is returned to normal position, and an arm carried by the door engaging said flexible element to assist in supporting the door in open position and to move the door to closed position when the body is moved to dumping and normal positions, respectively.

7. The combination with a support and a dump body mounted thereon for tilting movement to normal and dumping positions and having a door at one side hinged to swing open outwardly and downwardly substantially flush with the bottom of the body when the body is tilted to dumping position, of a flexible element secured at opposite extremities to the door and support at such points as to pull the door closed when the body is returned to normal position, and an arm carried by the door extending inwardly therefrom and engaging said flexible element to space said element above the axis of the door hinge when the body is tilted to dumping position, the flexible element being entirely free from said body between said arm and support.

8. The combination with a support and a dump body hinged thereon for tilting movement to normal and dumping positions and having a door at one side hinged to swing open outwardly and downwardly substantially flush with the bottom of the body when the body is tilted to dumping position, of a flexible element secured at opposite extremities to the door and support, the point of attachment of said element to the support being lower down than the hinge between the body and support so that the door hinge moves toward and away from said point when the body is moved to dumping and normal positions, respectively, so that said element pulls the door to closed position when the body is returned to normal position, and slackens to permit the door to

- swing open when the body is moved to dumping position, and an inwardly extending arm carried by the door and engaging said element to space said element above the axis 5 of the door hinge when the body is tilted to dumping position, the flexible element being entirely free from said body between said arm and support.
9. The combination with a support and a dump body mounted thereon for tilting movement to normal and dumping positions and having a door at one side hinged at one edge of the bottom of the body to swing open downwardly, of a direct tension connection 15 between said door and support, free from the body excepting the door, and arranged to pull the door closed when the body is moved from dumping to normal position.
10. The combination with a support and a dump body mounted thereon for tilting movement to normal and dumping positions and having a door at one side hinged at one edge of the bottom of the body to swing open downwardly, of an arm carried by the door 25 extending inwardly therefrom, and a direct tension connection between said arm and support for pulling the door closed when the body is moved from dumping to normal position.
- 30 11. The combination with a support and a dump body mounted thereon for tilting movement to normal and dumping positions and having a door at one side hinged at one edge of the bottom of the body to swing 35 open downwardly, of a flexible tension connection between and connected to said support and door and adapted to pull the door closed when the body is returned to normal position from dumping position, and means 40 engaged with said connection at a point between and at fixed distances from the door and support to cause said connection to
- flex at said point when the body is moved to dumping position and to support said connection above the door hinge. 45
12. The combination with a support and a dump body mounted thereon for tilting movement to normal and dumping positions and having a door at one side hinged at one edge of the bottom of the body to swing open 50 downwardly, of a tension connection connected at opposite extremities to said support and door and having a flexible portion between said extremities, said connection being arranged to pull the door closed when 55 the body is returned to normal position from dumping position, and means engaged with said flexible portion of said connection at fixed distances from the door and support to cause said connection to flex when the 60 body is moved to dumping position and arranged to support said connection above the door hinge.
13. The combination with a support and a dump body mounted thereon for tilting 65 movement to normal and dumping positions and having a door at one side hinged at one edge of the bottom of the body to swing open downwardly, of a flexible tension connection between and connected to said support 70 and door and adapted to pull the door closed when the body is returned to normal position from dumping position, and means engaged with said connection at a point between the door and support and at fixed distances from the points of connection of said connection with the door and support, to cause said connection to flex at said point when the body is moved to dumping position and to support said connection above 75 80 the door hinge.

In testimony whereof I hereunto affix my signature.

JOHN RICE, JR.
